CLAIM

The ornamental design for a configurable caged ball insert for a downhole tool, as shown and described.

DESCRIPTION

FIG. 1 is a perspective view of a configurable caged ball insert for a downhole tool;

FIG. 2 is a bottom plan view thereof;

FIG. 3 is a front side plan view thereof, wherein the front side plan view and the back side plan views are identical;

FIG. 4 is a top plan view thereof; and,

FIG. 5 is a left side plan view thereof, wherein the left side plan view and the right side plan views are identical.

The broken lines in the drawings depict unclaimed environmental subject matter.
